PLUG RETRIEVER

Eldon C. Foley, Columbus, Ohio

Application June 18, 1958, Serial No. 742,818

5 Claims. (Cl. 43—17.2)

The invention disclosed in this application relates to fishing equipment. The disclosure comprises an embodiment of my invention, consisting of a mechanism for retrieving fishing plugs (or lures, or artificial bait, or fishing hooks) when the same have been snagged or otherwise caught or entangled beneath the water.

An object of my invention is the provision of a plug retriever of simple construction, positive action and convenient for use.

A further object of my invention is the provision in such a construction of a sectional rigid handle for positively manipulating the plug retriever.

A further object of my invention is the provision in such a construction of a plug retriever comprising a can having a helical slot in a side wall extending from the open end thereof to a rounded hole in said side wall intermediate the ends thereof.

Further objects and features of the invention should be apparent from the following description and claims when considered in connection with the accompanying drawings illustrating an embodiment of my invention.

In the drawings:

Fig. 1 is a view in perspective illustrating an embodiment of my invention;

Fig. 2 is an end view in elevation on an enlarged scale showing the can utilized in my plug retriever; and

Fig. 3 is a side view in elevation also on an enlarged scale and also showing the can utilized in my plug retriever.

Referring still to the drawings for a detailed description of the embodiment illustrating my invention it may be seen that I have shown a sectional rod 11 made up of a plurality of sections such as for example the sections 12, 13 and 14. These sections of the rod are each hollow at one end and have such hollow threaded with a female thread and each has a tubular projection at the opposite end with a male thread of such size and shape that the projection fits into the hollow and the male thread thereon cooperates with the female thread to fasten each section of the rod to the next adjacent section. Thus the section 13 has a projection 15 which fits in the hollow at 16, in the section 14, and the tubular projection 15 is threaded securely into the hollow at 16. The projection 17 at the opposite end of the section 14 is threaded into the can 18 as will subsequently be described.

The can 18 shown best in Figs. 2 and 3 comprises a cylindrical member 21 having one end closed by a plug 22 and having the opposite end 23 open. The member is provided with a circular hole 24 intermediate its ends and with a helical slot 25 extending from the hole 24 to the end 23. The plug 22 is formed with a threaded cen-

2

tral bore 25 with which the projection 17 cooperates to secure the section 14 of the rod 13 to the can 18.

The operation of the embodiment of my invention to retrieve a snagged plug will now be described. The device will be carried by the fisherman normally in its disassembled condition with the sections 12, 13 and 14 separated from the can 18 and from each other. When a plug becomes snagged the fisherman takes the can 18 and puts it on the fish line so that the fish line is inserted through the slot 25 and finally passes through the hole 24. Then the sections 14, 13, 12, etc. are secured to the can and to each other and by means of the rod 11, the can 18 is pushed down to the snagged plug. By the action of the open ended can 18 as controlled positively by the rigid rod 11, the plug is efficiently removed from the obstruction and thereafter protected by can 18 is lifted to the surface. The fish line is easily removed from the can by being led out the slot 25 and the fisherman resumes his fishing.

It is to be understood that the above described embodiment of my invention is for the purpose of illustration only and various changes may be made therein without departing from the spirit and scope of my invention.

I claim:

1. A device for retrieving fishing equipment comprising in combination a tubular can having one end open and one end closed by a threaded plug and having its sides formed with a round hole intermediate the ends thereof and with a helical slot leading from said hole to said open end and a rigid rod made up of a plurality of sections threadedly secured to each other and to said can.

2. A device for retrieving fishing equipment comprising in combination a tubular can having one end open and one end closed and having its sides formed with a round hole intermediate the ends thereof and with a helical slot leading from said hole to said open end and a rigid rod made up of a plurality of sections threadedly secured to each other and to said can.

3. A device for retrieving fishing equipment comprising in combination a tubular can having one end open and one end closed by a threaded plug and having its sides formed with a round hole intermediate the ends thereof and with a slot leading from said hole to said open end and a rigid rod made up of sections secured to each other and to said can.

4. A device for retrieving fishing equipment comprising in combination a tubular can having one end open and one end closed and having its sides formed with a hole intermediate the ends thereof and with a slot leading from said hole to said open end and a rigid rod secured to said can.

5. A device for retrieving fishing equipment comprising in combination a tubular can having one end open and one end closed by a threaded plug and having its sides formed with a round hole intermediate the ends thereof and with a helical slot leading from said hole to said open end and a rigid rod secured to said can.
